UNITED STATES PATENT OFFICE.

JACOB LOSLI, OF PORTLAND, OREGON.

DESIGN FOR A LANTERN.

No. 37,856.

Specification for Design.

Patented Feb. 27, 1906.

Application filed August 16, 1905. Serial No. 274,506. Term of patent 14 years.

To all whom it may concern.

Be it known that I, JACOB LOSLI, a citizen of the United States, and a resident of Portland, county of Multnomah, State of Oregon, have invented a new, original, and ornamental Design for Lanterns, of which the following is a specification, reference being had to the accompanying drawings, forming a part thereof.

In such drawings, Figures 1 and 2 show,

respectively, one of the alternating faces of my lantern.

I claim—

The ornamental design for a lantern as herein shown.

JACOB LOSLI.

In presence of—

F. J. GEISLER,
R. V. MEIKLE.
